REFUSE COMPACTOR CABINET

Charles S. Bassin, Longmeadow, Mass., assignor to The Compactor Corporation, Chicopee, Mass.

Filed Sept. 11, 1972, Ser. No. 287,910

Term of patent 14 years

Int. Cl. D7—07

U.S. Cl. D7—194

The figure is a perspective view of a refuse compactor cabinet showing the design.

The rear of the cabinet is conventionally plain throughout and the side not shown is substantially identical to that shown.

I claim:

The ornamental design for a refuse compactor cabinet, as shown and described.
